UNITED STATES PATENT OFFICE.

DAVID FRANK, OF BROOKLYN, NEW YORK, ASSIGNOR OF ONE-HALF TO
JOHN TROUNSTINE, OF NEW YORK, N. Y.

DESIGN FOR AN END FRAME FOR BEDSTEADS.

SPECIFICATION forming part of Design No. 34,193, dated March 5, 1901.

Application filed February 9, 1901. Serial No. 46,742. Term of patent 7 years.

To all whom it may concern:

Be it known that I, DAVID FRANK, a citizen of the United States, residing at Brooklyn, Kings county, New York, have invented and produced a new and original Design for an End Frame for Bedsteads, of which the following is a specification, reference being had to the accompanying drawing, forming a part thereof, and in which is represented a front elevation of an end frame for bedsteads bearing and incorporating my design.

The leading features of my design consist of the form and ornamental configuration of the end frame, substantially as shown.

In the drawing, A A designate the corner-posts of the end frame, B B the transverse rods, extending intermediate said corner-posts, and C C the usual vertical rods, extending intermediate the transverse rods B B.

The distinctive ornamental part of the present design is located at the upper portion of the end frame and comprises the upper rod B, the central oval panel or field D, and curved end rods E E, the latter defining fields, within which are the scrolls F, while within the panel D are disposed the scroll-rods G, the whole being substantially as shown.

What I claim is—

The design for an end frame for bedsteads, substantially as shown and described.

Signed at Brooklyn, in the county of Kings and State of New York, this 5th day of February, 1901.

DAVID FRANK.
